SLUG CASTING MACHINE

Richard R. Mead, Queens Village, N. Y., assignor
to Mergenthaler Linotype Company, a corpora-
tion of New York

Application May 15, 1934, Serial No. 725,704

14 Claims. (Cl. 199—47)

This invention relates to slug casting machines of the general organization represented in U. S. Letters Patent No. 436,532 to O. Mergenthaler, wherein a composed line of matrices is presented momentarily to one face of a slotted mold, a metal pot brought against the opposite face of the mold, and molten metal injected by a pump from the metal pot into the mold slot or cavity to form a type bar or slug against the line of matrices.

The type bars or slugs produced in this way, besides being used for direct printing, are employed extensively for the production of stereotype matrices from which stereotype plates are then cast for printing. However, the printing processes which have recently come into use, especially in newspaper work, require much greater pressure to be exerted upon the slugs than heretofore in making up the stereotype matrices. This is especially true in the production of stereotypes by the so-called "dry flong" method, and it has been found in practice that some of the slugs have a tendency to break down under the increased pressure, this tendency being due to a spongy texture of the slugs caused by the presence therein of air holes which result from the mixing of air with the molten metal during the casting operation. Furthermore, the mixing of air with the molten metal often produces air holes in the character-bearing surfaces of the slugs, resulting in the production of imperfect impressions.

This mixing of air with the molten metal during casting is due either to improper venting of the mold cavity or to improper injection of the molten metal thereinto, or both. Various factors contribute to the improper injection of molten metal into the mold cavity, and although great advances have been made to overcome the difficulties encountered and to keep up with the modern trend in printing, nevertheless the developments up to the present time are not entirely satisfactory. However, before stating the advantages of the present invention and the manner in which existing difficulties are obviated by it, a few words of explanation may be useful.

The delivery passage formed in the throat section of the metal pot extends upwardly and forwardly from the pump cylinder to the mold contacting surface, which may be either an integral part of the throat section or a detachable mouthpiece. The discharge end of the delivery passage flares laterally so that its width is approximately equal to the length of the longest mold slot (in some machines 42 ems), and the height

of the delivery passage at this point is approximately equal to the thickness of the body of the largest slug or type bar which the particular machine is adapted to cast, usually a so-called ribbed or skeleton slug. The area of the delivery passage is such that ordinarily a uniform volume of metal can be forced therethrough by the metal pump at a sufficient rate of flow and under sufficient pressure to fill the mold completely and to expel all the air therein before the metal in the mold begins to solidify, and this volume is determined so that it will be sufficient when slugs are cast having a character-bearing portion which overhangs the slug body.

Heretofore, it was found that a single row of discharge openings in the mouthpiece of the throat section was not adequate to allow the rapid passage of a sufficiently large quantity of metal for casting the large ribbed slugs. To make the holes larger was impractical because when the metal recedes in the delivery passage after casting the back suction of air is too great and difficulties arise when the mold is separated from the mouthpiece. For this reason, a plurality of superposed rows of discharge openings has been employed, but the arrangement is not wholly satisfactory because there is presented between the rows of openings a flat surface against which the metal forced through the delivery passage strikes and the resistance offered causes a swirl or eddy which impedes the proper flow of metal through the rows of openings and the metal which does pass into the mold becomes chilled and solidified before the mold is filled and the air completely exhausted therefrom. Because of this, the slugs are improperly cast to the extent that not only are their body portions structurally weak but their overhanging character-bearing surfaces are also weak and ragged, causing the slugs either to break down in use or to produce imperfections in the printed matter, as already stated.

The present invention is intended to overcome these and other difficulties and provides a metal pot having a throat section formed with a delivery passage in which there is provided means for diverting the metal forced therethrough into different paths of flow leading directly to the different superposed rows of discharge openings formed in the mold engaging portion of the throat section or mouthpiece. Specifically, the invention provides a wedge-shaped member arranged in the delivery passage adjacent the inner face of the mouthpiece, which tapers rearwardly into the passage and breaks it up into

separate channels leading directly to the different rows of discharge openings. As a further feature, this wedge-shaped member is movable either manually or automatically to clear or obstruct 5 one or more of the rows of discharge openings, as desired.

In carrying out the invention, two preferred 10 embodiments are proposed, one being manual in its operation and the other automatic. The former is intended for use in machines adapted to cast slugs having a wide range of body sizes and wherein the mouthpiece is formed with two or more superposed rows of discharge openings, the wedge-shaped member being movable to different 15 set positions to clear all rows of openings or to obstruct certain and clear other of the rows of openings. In the latter embodiment, the wedge-shaped member forms an integral part of a rectangular block arranged in a vertical slide directly 20 behind the mouthpiece. The block is formed with a pair of slots, one above and one below the wedge-shaped member and each of which is adapted to register with a row of discharge openings in the mouthpiece when the block occupies a certain position. The block is adapted to act 25 more or less as a shutter and to be moved vertically by a series of levers connected to a periodically movable part of the machine, so that just prior to the injection of metal into the mold it 30 will be moved to bring its slots into alignment with the rows of discharge openings in the mouthpiece and after the injection, and before the metal is allowed to recede in the delivery passage, will be returned to its original position 35 to close the rows of discharge openings and hence prevent a back suction of air into the delivery passage.

In the accompanying drawings, the invention 40 has been shown merely by way of example and in preferred form and obviously many modifications and variations thereof will suggest themselves to those skilled in the art without departing from the spirit of the invention. It is to be understood, therefore, that the invention is not 45 limited to any particular form or embodiment except insofar as such limitations are specified in the appended claims.

Referring to the drawings:

Fig. 1 is a front elevation of the discharge end 50 of the throat section, showing the mouthpiece partly broken away;

Fig. 9 is a side elevation of a portion of a linotype machine, partly broken away to show another embodiment of the invention;

Fig. 10 is a plan view of the embodiment shown 70 in Fig. 9;

Fig. 11 is a transverse sectional view of the discharge end of the throat section, showing the embodiment illustrated in Fig. 9 with the parts in one position; and

Fig. 12 is a view similar to Fig. 11, showing the parts in another position.

Referring first to Fig. 9: After the line of matrices **X** and expandible spacebands **Y** have been composed and delivered to the first elevator **A** in the regular manner, the latter, which is slidably mounted in the vise frame **B**, descends to present the composed line to the face of the slotted mold **C** carried by the rotatable mold disk **D**, whereupon the line of matrices is alined with the mold slot **C¹** and the line justified by the upward movement of the justification lever **E** and bar (not shown) controlled by the cam **F** mounted on the main cam shaft **F¹**. Subsequently, the metal pot **G**, supported by legs **G¹** pivotally mounted on the vise frame as at **B¹**, is rocked forwardly by the cam **F²** which engages with the roller **G²** carried by the resilient rocking lever **G³**. The forward rocking of the metal pot **G** brings the mouthpiece **G⁴** thereof into engagement with the rear face of the mold **C**. The mold slot **C¹** is thus closed at the rear by the mouthpiece **G⁴** and at the front by the justified line of matrices **X** and spacebands **Y** and is ready for the injection of molten metal to form a slug or type bar. The metal is injected in the well known manner by a plunger (not shown) arranged in a well in the metal pot **G** and carried by a plunger rod **H**, pivoted to a lever **H¹** normally held in raised position by the engagement of a roller carried thereby with the periphery of a cam mounted on the main cam shaft **F¹** and which in its rotation presents a depression in its periphery to allow the descent of the plunger in response to the action of a powerful spring pressure on the lever **H¹**.

As shown in Figs. 1 and 2, for example, the metal pot mouthpiece **G⁴** is formed ordinarily with a plurality of superposed discharge openings **g**, which aline with the mold slot **C¹** and communicate with a delivery passage **G⁵** leading rearwardly through the throat section **G⁶** to the pump well of the metal pot **G**. The mold slot **C¹** is determined by the fixed lower or body portion **c** and movable upper or cap portion **c¹** of the mold and the lower row of discharge openings **g** in the mouthpiece **G⁴** will always aline with the mold slot regardless of its size. If the cap portion **c¹** of the mold is raised for casting a thick (ribbed) slug, both rows of openings **g** register with the slot **C¹**, but when lowered beyond the level of the upper row of openings **g** for casting solid (ribless) slugs, the cap portion **c¹**, which is adapted to effect a metal tight seal with the front face of the mouthpiece **G⁴**, shuts off the flow of metal through the upper row of openings.

As thus far described the parts and their mode of operation, except as hereinafter pointed out, are or may be the same as embodied in the commercial machines and therefore require no further description.

Coming now to the present invention, there is provided in the delivery passage **G⁵**, adjacent the rear face of the mouthpiece **G⁴**, a wedge-shaped member **J**, which is arranged lengthwise of the passage intermediate the superposed rows of discharge openings **g**, and which tapers rearwardly into the passage (see Fig. 2) to form two separate channels **G⁷** and **G⁸**, leading directly to the upper and lower row of discharge openings **g**, respectively. In the embodiment illustrated in Figs. 1 and 2, the member **J** is detachably secured in fixed position to the throat section **G⁶**, as by 60 screws **J¹**. It will also be noted that the discharge openings **g** in the upper row are arranged at an upward inclination, being parallel to the upper inclined surface of the member **J** and forming a straight line continuation of the upper 70

channel G^7 , while the openings of the lower row are horizontal and form a straight line continuation of the lower channel G^8 . Hence, during the descent of the pump plunger to force molten metal 5 into the mold, the metal flows in a continuous stream through the delivery passage G^5 , but before reaching the mouthpiece G^4 it is diverted or broken up by the wedge-shaped member J into separate paths of flow leading directly to the two 10 rows of discharge openings g and into the mold, thus obviating the swirl or eddy occurring when the single stream of metal meets with the resistance of the normally existing flat wall G^9 and the resultant impeding of the direct and rapid flow 15 of metal through the opening g .

The direction of the metal through the discharge openings g is further aided by the construction of the inner face of the mouthpiece G^4 in the vicinity of each opening. With reference 20 to Fig. 3, it will be noted that a flared recess G^{10} is formed in the rear face of the mouthpiece in communication with each opening g , thus eliminating the presence of a flat wall of any appreciable area which would offer resistance to the 25 flow of metal.

In Figs. 4, 5 and 6 there is illustrated a modification of the invention, wherein the wedge-shaped member J is pivotally mounted in the delivery passage, being journaled at opposite 30 ends near its rear or thin edge in opposite side walls of the throat section. One journal pin J^2 (see Fig. 4) extends through the side wall of the throat section and has fixed to it a crank arm K , formed at its distal end with a bearing K^1 adapted to carry a spring detent L . The detent is normally held by a spring L^1 in projected position for engagement in one of a series of holes L^2 formed in a boss L^3 cast integrally with or otherwise secured to the throat section G^6 . The forward or thick edge of the member J is arcuate and adapted to ride in a curved-walled recess G^{11} formed in the mouthpiece G^4 .

With this arrangement, the retraction of the detent L permits the member J to be moved to any one of three different positions. For example, as shown in Fig. 5, the detent L engages in the center hole L^2 and the member J lies intermediate the two rows of discharge openings g , defining two separate channels G^7 and G^8 (just 45 as the embodiment shown in Fig. 2) leading directly to the upper and lower rows of openings g , respectively. This is the position that the member J occupies when a large mold is in use for casting a ribbed slug. If on the other hand, the mold in use is for casting a solid slug, the detent L is retracted and the crank K moved to the position shown by the heavy lines in Fig. 6, thereby 50 rocking the member J upwardly to close the upper row of discharge openings g and permit the passage of molten metal through the lower row of openings only. Likewise if it is desired to have only the upper row of openings g clear, the member J may be rocked downwardly to close the lower row of openings, as shown by the 55 light dotted lines in Fig. 6.

Referring to the embodiment shown in Figs. 7 and 8, the mouthpiece G^4 is formed with five superposed rows of discharge openings corresponding to the shape of a cored mold for casting 60 the large ribbed slugs, this arrangement permitting a more rapid and uniform injection of the metal into all parts of the mold cavity. It will be noted that the openings in the lowermost row are closely related and are adapted to aline 65 with the unbroken portion of the mold slot or

cavity C^1 (see Fig. 8) in which the solid body portion of the slug is cast, whereas the openings of the four upper rows are spaced apart laterally and are adapted to aline with the spaces between the cores C^3 in which the ribs for supporting the overhanging character-bearing portion of the slug are cast. The wedge-shaped member J is pivotally mounted in the delivery passage G^5 of the throat section in the same manner as that already described in connection with the embodiment shown in Figs. 5 and 6, and although the crank K is preferably provided with a depressible detent M for locking the member J in set position, a retractable detent such as that shown in Fig. 4 could be employed. 10

In this embodiment the wedge-shaped member J is movable to five different set positions, in each of which it may be locked by the engagement of the detent M in one of a series of slots M^1 formed in a boss M^2 on the throat section G^6 . 20 The forward or thick edge of the member J is of such size that in different positions it will close either one or two of the rows of openings. For example, in the position shown in Fig. 7 the member J closes only the central row of openings 25 indicated by the numeral 3, leaving clear or unobstructed the openings 1 and 2 above it and the openings 4 and 5 below it and defining, as in the instances already described, upper and lower channels G^7 and G^8 , respectively, leading directly 30 to the unobstructed upper and lower rows of openings. This is the position occupied by the member J when casting very large ribbed slugs having comparatively thick solid body portions. In casting ribbed slugs having thin body portions, 35 the member J is moved and the detent M seated in the notch M^1 indicated by the numerals 1, 2, 5, whereby the member J closes the rows of openings marked 3 and 4 and leaves rows 1, 2, 5 unobstructed, so that metal going into the formation 40 of the body portion of the slug is injected into the mold through the opening 5 and that going into the formation of the supporting ribs is injected through openings 1 and 2. On the other hand, if there is brought into position a mold 45 for casting a slug with small or narrow supporting ribs, the member J is rocked upwardly and the detent M seated in the slot M^1 marked with the numerals 3, 4, 5. In this position, the member J closes rows of openings 1 and 2, leaving 50 rows 3, 4 and 5 unobstructed, and serves to decrease the size of the delivery passage G^5 at the point of discharge and thus lessen the tendency for a swirl or eddy of the metal to occur and also reduce the area of the front face of the 55 mouthpiece which must have a metal-tight engagement with the rear face of the mold to prevent a metal squirt.

Coming now to the embodiment shown in Figs. 9 to 12, the member J is formed as an integral 60 part of a rectangular block R , arranged in a recess G^{12} formed in the throat section G^6 immediately behind the mouthpiece G^4 . The block R is slidable vertically in the recess G^{12} and is formed with slots r , one above and below the 65 member J , which are adapted to register with the discharge openings g in the mouthpiece when the block R is in its lowermost position, as shown in Fig. 12. When the block R is in its upper position, as shown in Fig. 11, it serves to obstruct 70 the discharge openings g and cut off communication of the delivery passage G^5 with the exterior.

In carrying out the automatic feature of the invention, the block R is formed at opposite ends 75

with pins R^1 , journaled in the ends of levers R^2 fixed to a rock shaft R^3 extending through the casing of the metal pot rearwardly of the discharge end of the throat section (see Fig. 10). 5 One of the levers R^2 is formed with an arm R^4 extending rearwardly and to the distal end of which there is pivotally attached, as at R^5 , a link R^6 , which extends downwardly and has its free end secured by a heavy tension spring R^7 to the 10 justification rod E , already mentioned. A tension spring R^8 , of less strength than the spring R^7 , has one end secured adjacent the distal end of the lever arm R^4 , as at R^9 , and its opposite end secured to a fixed pin R^{10} on the metal pot G . 15 In the operation of the machine, the spring R^7 , through the link R^6 and lever arm R^4 and against the pull of the spring R^8 , maintains the block R in its upper position as shown in Fig. 11. Just prior to the injection of molten metal into the 20 mold, the line of matrices X is justified by the expansion of the spacebands Y , which expansion is effected through a justification bar by the upward movement of the justification lever E in response to the action of a spring E^1 when a 25 roller E^2 on the lever E rides into a depression formed in the periphery of the cam F . When the justification lever rises, relieving the tension of the spring R^7 , the spring R^8 exercises itself to pull up on the lever arm R^4 to rock the shaft 30 R^3 and through the levers R^2 move the block R to its lower position as shown in Fig. 12. Immediately thereafter the mold is sealed by the line of matrices X and the mouthpiece G^4 (which heretofore have been but loosely engaged with 35 the mold) and molten metal is injected through the unobstructed channels formed by the slots r and discharge openings g . Subsequently, after the metal in the mold has solidified, the roller E^2 on the justification lever E rides out of the 40 depression in the cam F and forces the lever E downwardly to remove the justification bar from engagement with the spacebands Y and allow the latter to return to their unexpanded condition in the "unlocking" of the line of matrices 45 so that it may be withdrawn from engagement with the front face of the mold. As the lever E descends, the pull of the spring R^7 overcomes that of the spring R^8 to rock the lever arm R^4 downwardly and return the block R to its upper 50 position to shut off communication of the delivery passage G^5 with the exterior. The metal pot G then recedes to break the engagement of the mouthpiece G^4 with the rear face of the mold, but because the discharge openings g have been 55 obstructed by the block R the back suction of air into the delivery passage, which ordinarily takes place, is prevented.

The arrangement just described obviates several objectionable features of existing machines. 60 For example, when the back suction of air into the delivery passage G^5 occurs as the metal recedes in the passage, an oxidation of the metal clinging to the walls of the passage takes place, which, over a period of time, causes an accumulation 65 of oxidized metal and gradually lessens the area of the passage which, as already pointed out, is predetermined for a machine of definite capacity with respect to the volume of metal forced through the passage and the pressure by which 70 it is forced. In time, this accumulation becomes so great that the pump cannot force a sufficient volume of metal through the passage rapidly enough to completely fill the mold before the metal first to reach the mold is chilled and begins to 75 solidify. Moreover, all of the air which has been

sucked back into the delivery passage must be forced ahead of the metal into the mold and then completely exhausted. This coupled with the clogged passage which prevents the rapid injection of the metal gives rise to an improperly cast slug, weakened by the presence of air holes which exist because of the failure of the great volume of air to have been exhausted completely from the mold cavity before solidification of the metal, and a slug of this character, as stated heretofore, has a texture so spongy that not only are the characters formed with ragged edges which give rise to imperfect impressions, but the slug is too weak to stand the great pressures to which it is subjected in carrying out modern 15 printing methods.

Having thus described my invention, what I claim is:

1. In or for a slug casting machine, a metal pot, including, in combination, a throat section 20 formed with a passage through which molten metal is adapted to be forced into the mold, the discharge end of the throat section being formed with a plurality of superposed rows of discharge openings, and means arranged in the passage of 25 the throat section for diverting the metal flowing through the passage into different paths of flow to the rows of openings.

2. In or for a slug casting machine, a metal pot, including, in combination, a throat section formed 30 with a passage through which molten metal is adapted to be forced into the mold, the discharge end of the throat section being formed with a plurality of superposed rows of discharge openings, and means arranged in the passage of 35 the throat section adjacent the inner face of the mold engaging portion and tapering rearwardly into said passage for diverting the metal flowing through the passage into different paths of flow to the rows of openings.

3. In or for a slug casting machine, a metal pot, including, in combination a throat section formed with a passage through which molten metal is adapted to be forced into the mold, a mouthpiece for said throat section formed with 45 a plurality of superposed rows of discharge openings, and means arranged in the passage of the throat section adjacent the inner face of the mouthpiece for diverting the metal flowing through the passage into different paths of flow 50 to the rows of openings.

4. In or for a slug casting machine, a metal pot, including, in combination, a throat section formed with a passage through which molten metal is adapted to be forced into the mold, a 55 mouthpiece for said throat section formed with a plurality of superposed rows of discharge openings, and means arranged in the throat passage and extending throughout the width thereof and tapering rearwardly thereinto from the inner face 60 of the mouthpiece to divert the metal flowing through the passage into a plurality of separate passes leading directly to the different rows of openings, the openings of each row being formed in the mouthpiece as straight line continuations 65 of the pass with which they register.

5. A combination as set forth in claim 1, wherein in the means for diverting the flow of metal through the throat passage is movable to close one or more of the rows of discharge openings. 70

6. A combination as set forth in claim 1, characterized by the fact that two rows of discharge openings are provided, and wherein the means for diverting the flow of metal is mounted in the throat passage and movable to different positions 75.

to close one or the other of said rows of openings, as desired.

7. A combination as set forth in claim 1, characterized by the fact that two rows of discharge openings are provided, and wherein the means for diverting the flow of metal is mounted in the throat passage and movable to different positions to close one or the other of said rows of openings or leave both rows open, as desired.

10 8. A combination as set forth in claim 1, characterized by the fact that two rows of discharge openings are provided, and wherein the means for diverting the flow of metal is a wedge-shaped member journaled at opposite ends in the side walls of the throat section, and including means operable to rock said member to different positions to close one or the other of said rows of openings, as desired.

9. A combination as set forth in claim 1, characterized by the fact that two rows of discharge openings are provided, and wherein the means for diverting the flow of metal is a wedge-shaped member journaled at opposite ends in the side walls of the throat section, and including means operable to rock said member to different positions to close one or the other of said rows of openings or leave both rows open, as desired, and means for locking said member in any of its different positions.

30 10. A combination as set forth in claim 1, characterized by the fact that more than two rows of discharge openings are provided, and wherein the means for diverting the flow of metal is mounted in the throat passage and movable to different positions to close one or more of said rows of openings.

11. A combination as set forth in claim 1, characterized by the fact that more than two rows of discharge openings are provided, and wherein the means for diverting the flow of metal is mounted in the throat passage and movable to different positions to close one or more of said rows of openings, and including means for moving said metal diverting means and maintaining the same in any of its different positions.

45 12. In a slug casting machine, the combination of a metal pot having a throat section formed with a passage through which molten metal is forced into the mold for casting, said passage opening to the exterior through a plurality of superposed rows of discharge openings above the level of metal in the throat section,

means movably arranged in the passage through the throat section for obstructing and clearing said rows of openings, said means normally occupying an obstructing position, and connections between said means and a periodically movable part of the machine for effecting the movement of said means to clear the openings for the discharge of metal during casting.

13. In a slug casting machine, the combination of a metal pot having a throat section formed with a passage through which molten metal is forced into the mold for casting, said passage opening to the exterior through a plurality of superposed rows of discharge openings above the level of metal in the throat section, means movably arranged in the passage through the throat section for obstructing and clearing said rows of openings, and being formed to divert metal into separate paths of flow to the rows of openings when in clearing position, said means normally occupying an obstructing position, and connections between said means and a periodically movable part of the machine for effecting the movement of said means to clear the openings for the discharge of metal during casting.

14. In a slug casting machine, the combination of a metal pot having a throat section formed with a passage through which molten metal is forced into the mold for casting, said passage opening to the exterior through a plurality of superposed rows of discharge openings above the level of metal in the throat section, said openings being formed in a mouthpiece secured to the throat section, a shutter arranged in the throat passage adjacent the inner face of the mouthpiece and having a limited vertical movement, means forming a part of the shutter for diverting the flow of metal in the passage through the throat section into separate passes, openings in the shutter forming a communication between said passes and the rows of openings in the mouthpiece, means for yieldably holding the shutter in a position with its communicating openings out of registry with the openings in the mouthpiece, and connections with a periodically movable part of the machine for moving the shutter in opposition to its yieldable holding means to momentarily bring its communicating openings into registry with the openings in the mouthpiece for the discharge of metal during casting.

RICHARD R. MEAD.
